UNITED STATES PATENT OFFICE.

FREDERICK SCHWANHAUSSER, OF NEW YORK, N. Y.

PROJECTING APPARATUS.

No. 826,446.

Specification of Letters Patent.

Patented July 17, 1906.

Application filed April 6, 1906. Serial No. 310,273.

To all whom it may concern:

Be it known that I, FREDERICK SCHWANHAUSSER, a citizen of the United States, and a resident of the city of New York, borough of Manhattan, in the county and State of New York, have invented new and useful Improvements in Projecting Apparatus, of which the following is a full, clear, and exact description.

10 The object of the invention is to provide certain new and useful improvements in projecting apparatus, such as a combined dissolving stereopticon and a moving-picture apparatus, whereby only two lamps are required, one of the lamps being capable of being bodily shifted in a lateral direction to assume an active position either for one of the stereopticon-lanterns or for the moving-picture apparatus.

20 The invention consists of novel features and parts and combinations of the same, which will be more fully described hereinafter and then pointed out in the claims.

A practical embodiment of the invention is 25 represented in the accompanying drawings, forming a part of this specification, in which similar characters of reference indicate corresponding parts in all the views.

Figure 1 is a side elevation of the improvement. Fig. 2 is a rear end elevation of the same; and Fig. 3 is a perspective view of the supporting-bracket for the upper lantern.

Three projecting apparatus A, B, and C, having two lamps D and E, with condensers D' E' attached thereto, are mounted on a suitable base F, the said projecting apparatus A and B being preferably located one above the other and forming the lanterns of a dissolving stereopticon, while the projecting apparatus C is preferably a moving-picture apparatus and is located adjacent and parallel to the lower lantern B of the stereopticon. The lamp D and its condenser D' form a permanent part of the upper lantern A, while the lower lamp E and its condenser E' are bodily shiftable in a transverse direction to become the source of light for either the lantern B or the moving-picture apparatus C—that is, the lamp E and its condenser E' can be moved into axial alinement with either the said lantern B or the moving-picture apparatus C.

For the purpose described a bracket G is secured on the base F and is provided at its upper end with a horizontal member supporting a transverse pivot G', on which the

framework of the upper lantern A is mounted to swing, a suitable adjacent device H (see Fig. 1) being employed and connected with the framework of the upper lantern A to bring the same in proper axial position relative to the lantern B.

By reference to Fig. 2 it will be seen that the bracket G leaves a free and unobstructed passage for the lamp E and its condenser E' to allow of shifting this lamp E and its condenser E' transversely into axial alinement with either the lower lantern B or the moving-picture apparatus C. The lamp E, with the condenser E' attached thereto, is mounted on a base I, having depending lugs I' I'', slidably engaging transverse rods J, secured in sleeves K, mounted to slide longitudinally on guideways L, supported on brackets M, attached to the base F. Now by the arrangement described the lamp E can be moved in a longitudinal direction, as well as in a transverse direction, so as to bring the lamp E in proper axial alinement with either the lower lantern B or the moving-picture apparatus C.

By reference to Fig. 2 it will be seen that the depending lugs I' I'' are limited in their sliding movement on the guideways J by butting against the sleeves K to insure at all times a proper alinement of the lamp E with the corresponding lantern B or the moving-picture apparatus C.

From the foregoing it will be seen by the arrangement described that it is only necessary to use two lamps for three projecting apparatus, it being understood that when the dissolving stereopticon is used the moving-picture apparatus is not employed and when the moving-picture apparatus is used the dissolving stereopticon is not employed.

Having thus described my invention, I claim as new and desire to secure by Letters Patent—

1. An apparatus of the class described, comprising three projecting apparatus having two lamps, two of the projecting apparatus being arranged one above the other, and the other at one side of one of the said first two projecting apparatus, one of the lamps forming part of one of the first two projecting apparatus and the other lamp being bodily movable, to be used in connection with the other of the two projecting apparatus.

2. An apparatus of the class described, comprising a dissolving stereopticon and a

moving-picture apparatus, the said stereopticon and the said moving-picture apparatus having two lamps, of which one forms a permanent part of one of the stereopticon-lanterns and the other lamp is bodily movable to active position for either the said moving-picture apparatus or the other lantern of the stereopticon.

3. An apparatus of the class described, comprising a base, a dissolving stereopticon having two lanterns one above the other, a bracket on the said base for supporting the lamp of the upper lantern, a transverse guideway held on the said base and on which the lamp for the lower lantern is bodily movable, and an independent projecting apparatus mounted on the said base and adapted to secure its source of light from the said bodily-movable lamp when the latter is shifted into axial alinement with the said projecting apparatus.

4. An apparatus of the class described, comprising a base, a dissolving stereopticon having two lanterns one above the other, a bracket on the said base for supporting the lamp of the upper lantern and allowing transverse movement of the lamp for the lower lantern, a transverse guideway held on the said base and on which the lamp for the lower lantern is bodily movable, and an independent projecting apparatus mounted on the said base and adapted to secure its source of light from the said bodily-movable lamp when the latter is shifted into axial alinement with the said projecting apparatus.

5. An apparatus of the class described, comprising a base, a dissolving stereopticon having two lanterns one above the other, a bracket on the said base for pivotally supporting the lamp of the upper lantern, a transverse guideway held on the said base and on which the lamp for the lower lantern is bodily movable, and an independent projecting apparatus mounted on the said base and adapted to secure its source of light from the said bodily-movable lamp when the latter is shifted into axial alinement with the said projecting apparatus.

6. An apparatus of the class described, comprising a base, a dissolving stereopticon having two lanterns one above the other, a bracket on the said base for supporting the lamp of the upper lantern, a transverse guideway held on the said base and on which the lamp for the lower lantern is bodily movable, an independent projecting apparatus mounted on the said base and adapted to secure its source of light from the said bodily-movable lamp when the latter is shifted into axial alinement with the said projecting apparatus, and means for limiting the transverse sliding movement of the lamp for the said lower lantern.

In testimony whereof I have signed my name to this specification in the presence of two subscribing witnesses.

FREDERICK SCHWANHAUSER.
